UNITED STATES PATENT OFFICE.

JOHN A. McNELLY AND CLARENCE E. JONES, OF DESLOGE, MISSOURI.

FLOOR LAMP.

Application filed February 26, 1926. Serial No. 90,800.

Our present invention pertains to floor lamps, and contemplates the provision of a peculiar and advantageous floor lamp possessed of the practical advantages herein-
5 after ascribed to it.

The invention consists in the improvement as hereinafter described and claimed.

In the accompanying drawings, forming part of this specification:—

10 Figure 1 is a side elevation of the floor lamp constituting the best practical embodiment of our invention of which we are cognizant.

Figure 2 is an enlarged fragmentary inverted plan view illustrative of the manner in which the feet of the lamp are joined to the center column.

Figure 3 is an inverted plan view showing the lamp base and the weight disposed in 20 and carried by said base with a view to lending increased stability to the lamp.

Similar numerals of reference designate corresponding parts in all of the views of the drawings.

25 Among other elements our novel lamp comprises a center column or upright 1, preferably of the shape in cross-section illustrated in Figures 1 and 2. The said center column 1 is tapered upwardly, and is de-

signed to be equipped at its upper end with 30 an appropriate electric light fixture and shade as shown by full lines and dotted lines in Figure 1. At its lower end the center column 1 is mortised, as designated by 2 in

35 Figure 2 for the reception of the tongue-like end 3 of feet 4; the feet being preferably of ornamental configuration and the tongue 3 of the feet being connected to the center column 1 through the medium of wood

40 screws 5. An ornamental cap 6, Figures 1 and 3, is connected by screws 7 to the lower end of the center column 1 for the purpose of adding to the finish of the lamp by covering the joints between the feet 4 and the

45 center column 1.

As will be understood from Figure 1, the feet 4 are superposed upon a base 8, the feet being preferably fastened to the base by countersunk screws. The base 8 is of open 50 form, and preferably, though not necessarily, of octagonal configuration, Figure 3, and in the underside of the base is provided a cham-

ber 9 for the reception of weights 10 which are connected to the base, preferably through the medium of wood screws 11, and are designed to lend increased weight to the base so as to contribute to the stability of the lamp and in that way avert casual tipping of the lamp, and this without interfering in appreciable measure with the facility with 55 which the lamp may be moved from one point in a room to another.

In accordance with one part of our invention, we prefer to equip the center column 1 with a table, designated by 12, and shown in Figure 1. The said table has a center aperture to permit of the same being slipped downwardly on the center post or column 1 and so that the table 12 will come to a rest at a predetermined height above the floor. When positioned as indicated, the table 12 is fixed with respect to the center column 1 through the medium of braces 13, grouped 60 about the center column 1 and fastened to the underside of the table 12 and also fastened to the column 1 through the medium 65 of wood screws.

It will be apparent from the foregoing that a floor lamp characterized as stated is, 70 at once, simple, strong, and ornamental in appearance; also, that by virtue of the construction described the lamp is susceptible of easy and inexpensive production, and is adapted to be stored or shipped in knock-down state and to be assembled or fabricated 75 into a complete lamp with facility and without the employment of skilled labor or tools other than an ordinary screw driver.

While we prefer the construction as illustrated and specifically described, we do not desire to be understood as limiting ourselves to the precise construction and arrangement of elements as disclosed, our invention being defined by our appended claim within the scope of which modifications in structure and in arrangement may be made without departure 80 from our invention.

Having described our invention, what we claim and desire to secure by Letters-Patent, 85 is:—

In a floor lamp, and in combination, a base, a center column arranged with its lower end above and in spaced relation to the base and having in its lower end portion

2
mortises and legs grouped about the lower portion of the center column and superposed upon and connected to the base and having 5 tongues or reduced upper portions let into the mortises of the center column and connected to said tongues, with a member opposed and connected to the lower end of the center column below the mortises therein and the reduced portions or tongues of the legs to hide the joints between the legs and 10 the center column from view.

In testimony whereof we affix our signatures.

JOHN A. McNELLY.
CLARENCE E. JONES.
